CARTRIDGE-TYPE TAPE RECORDER

James H. Tolar, Mayfield Heights, Ohio, assignor to
Tenna Corporation, a corporation of Ohio

Filed Dec. 21, 1966, Ser. No. 5,141

Term of patent 7 years

(Cl. D26—14)

BY

FIGURE 1 is a front view of a cartridge-type tape recorder incorporating my new design.

FIGURE 2 is a top view of the tape recorder.

FIGURE 3 is a rear view of the tape recorder.

FIGURE 4 is a side view of the tape recorder.

FIGURE 5 is a perspective view of the tape recorder.

The dominant features of the new design are shown in solid lines in the drawing.

I claim:

The ornamental design for a cartridge-type tape recorder, as shown and described.
